UNITED STATES PATENT OFFICE.

OTTO M. HOCH, OF ROCHESTER, NEW YORK, ASSIGNOR TO M. D. KNOWLTON COMPANY,
OF ROCHESTER, NEW YORK, A CORPORATION OF NEW YORK.

SHEET-TRIP.

1,296,803.

Specification of Letters Patent. Patented Mar. 11, 1919.

Application filed April 11, 1917. Serial No. 161,379.

To all whom it may concern:

Be it known that I, OTTO M. HOCH, a citizen of the United States, and resident of Rochester, in the county of Monroe and 5 State of New York, have invented certain new and useful Improvements in Sheet-Trips, of which the following is a specification.

This invention relates to sheet trips for 10 use in connection with mechanism for performing certain operations upon a moving web of material, the sheet trip being used to control the operation of said mechanism.

The primary object of the present invention 15 resides in the provision of a sheet trip which is actuated by the forward edge of the moving web of material to mechanically control the clutch members which set in motion the mechanism for operating upon the 20 web of material.

The present invention is adapted to be employed in connection with mechanism for shearing a moving web of material into sheets of various lengths, such as disclosed 25 in the co-pending application, Serial No. 67,799, filed Dec. 20, 1915. In said application, the mechanism disclosed includes, broadly, means for feeding a web of material, means for shearing the web transversely 30 into sheets while the web is in movement, which means is actuated and controlled by a clutch, and means for controlling the clutch so that its members will be interengaged when the proper length of material has been 35 fed and is ready to be sheared. Specifically, the present invention relates to the means for controlling the engagement and disengagement of the clutch members. It will be understood, however, that the sheet trip 40 herein described and claimed may be used in various other connections with equal facility, and the invention should, therefore, not be considered as limited to the specific machine herein referred to.

45 In the drawings:—

Figure 1 is a sectional view through the machine showing the location of the respective elements of the present invention;

Fig. 2 is an enlarged detail of a portion 50 of the machine illustrating the trip case and its associated parts and the clutch-controlling cam with its associated parts;

Fig. 3 is an enlarged side elevation of said clutch-controlling cam and the mechanism 55 for actuating the clutch, together with the

means for rendering the mechanism operative under the action of the web of material or by hand, or for locking the same;

Fig. 4 is an enlarged detail of the trip casing, trip lever and associated parts; 60

Fig. 5 is a similar view looking at right angles to Fig. 1; and

Fig. 6 is a detail of the latch and the controlling pawl therefor.

Referring to the drawings, and particularly to Fig. 1, the machine disclosed therein includes a plurality of feed rollers which are arranged in pairs and are indicated generally by the reference character R. These rollers feed the web of material, which is to be operated upon, over a table T and between the knives K and K' of the shear mechanism, and thence on to the moving belts B which convey the sheared sheet of material from the machine. The particular construction 75 of these parts need not be here described in detail, as they form no part of the present invention, but it is to be noted that the shear mechanism which travels with the web of material during the shearing operation is rendered operative by a clutch and co-operating mechanism, such as set forth in the co-pending application, Serial No. 67,818, filed December 20, 1915. The shearing operation takes place when the arrival of the 80 leading edge of the web of material reaches the sheet trip, which is herein designated generally by the reference character S. The clutch referred to is, as in the last-mentioned co-pending application, controlled by a 85 clutch rod 1, which rod is pivoted at 2, on an arm 3. This arm 3 is secured to a shaft 4 which is supported in a bracket 5 carried by the frame of the machine. Mounted loosely on the shaft 4 is a cam lever 6 which carries 90 a roller 7 at its upper or free end. This roller 7 is adapted to co-operate with a cam 8 which is provided with high and low portions, as illustrated in Fig. 3 of the drawings, and is mounted on a crank shaft 9, 100 which shaft is actuated by the engagement of the clutch members, above referred to, in the manner disclosed in the last-mentioned co-pending application. This cam roller 7 is normally maintained in engagement with the surface of the cam by a spring 10 which is secured to the cam lever and to a stationary portion of the frame at 11. An arm 12 is secured to the shaft 4 and carries at its upper end, a pivoted pawl 13 which is ar-

95

100

105

110

ranged to engage a wear-block 14 on the cam lever 6, as disclosed in Fig. 3. This pawl 13 is adapted to be moved out of engagement with said wear-block 14 by a rod 15 which is secured to the pawl and has a lost motion connection at 16 with an arm 17 carried by and rigid with a shaft 18, which shaft is mounted in suitable brackets 19 on the frame of the machine. A second arm 20 extends from this shaft 18 and is connected to a bell crank lever 21 by means of a connecting link 22. This lever 21 is attached to a crank arm 23, which is mounted rigidly on an oscillatory shaft 24, by means of a connecting rod 25. This shaft 24 is carried by the trip casing S, as disclosed in Fig. 4 of the drawings. The rod 25 passes through a bracket 26 and is provided with a collar 27, between which collar and bracket a coil spring 28 is mounted and surrounds the rod 25, which spring, when relieved of its confinement, moves the rod 25 and, through the connecting elements, lifts the pawl 13 from engagement with the wear-block 14. Thus, when the shaft 24 is permitted to oscillate so that the arm 23 thereon will move to the left in Fig. 3, under the action of the spring 28, the pawl 13 will be lifted from its engagement with the block 14 and the clutch rod 1 permitted to move under the influence of its actuating spring (not shown) to engage the clutch members so that the shearing mechanism will be actuated.

In order that the parts may be reset and the spring 28 again placed under compression, a cam lever 29 is loosely mounted on the shaft 4 and is provided with a roller 30, which is normally maintained in engagement with the face of the cam 8 by a spring 31. Rigid with and extending in angular relation to the cam lever 29 is an arm 32, which is connected, by a lost motion connection through a link 33, with the arm 17. Thus, when the cam 8 is rotated after the clutch members have been engaged, as previously described, the riding of the roller 30 on the high portion of the cam 8 will cause the downward movement of the link 33, and the consequent reengagement of the pawl 13 with the wear-block 14, and the placing of the spring 28 under compression, so that it will be ready for a subsequent operation.

In order that the rod 25 may be permitted to move at the proper times to cause the interengagement of the members of the clutch, and the consequent operation of the shearing mechanism, the sheet trip, which has been previously referred to and designated by the reference character S, is provided. This trip includes a casing, which, as aforesaid, supports the shaft 24 and which is adjustably mounted on a graduated tube 34, with the graduations 35 of which a pointer 36 on

position of the casing when it is desired to shear the web of material into sheets of predetermined lengths. This casing is moved on the tube 34 by means of a hand-wheel 37 which operates a pinion 38 through a train 70 of gears and pinions, which are indicated in dotted lines in Fig. 4 and which are not herein described, as the particular means forms no part of the present invention and as they are described in the afore-mentioned co-pending application, Serial No. 67,818. A trip lever 39 is pivoted on a shaft 40 on the trip casing and is provided with fingers at its lower end which are faced with wear-plates 41, which fingers extend through 75 slots in the stripper 42. This stripper is pivoted to the trip casing at 43 at its forward end is movable vertically at its rear end, being guided by a bolt 44 which depends from the casing. The web of material as it is fed beneath the stripper 42 is acted on by pressure rolls 42' which are arranged on the sides of the trip casing and are mounted on the transversely-extending pin 43'. The lower end of the trip lever 39 lies in the path 80 of movement of the web of material which passes beneath the stripper 42, and by which latter, the upper liner of the web, when the latter is corrugated board, is prevented from curling. This lower end of the trip lever 90 95 is maintained in its forward position by means of a spring 45 which is attached to an arm 46 on the lever and forces the lower end of the lever into engagement with a stop 47 on the casing. Pivoted loosely on the 100 shaft 40 is a latch 48, which is of angular form, and is provided with an extending portion arranged to engage a latch arm 48', which is keyed to the shaft 24, so that it will oscillate with the latter, but so that 105 it will move with the casing and with relation to the shaft. This latch arm 48' is provided at its lower end with a shoe 49, for a purpose which will later become apparent. This latch 48 is normally held in the path 110 of movement of the latch arm 48' so that the movement of the latter, under the influence of the spring 28, is prevented, by a spring 50. A pawl 51 is pivoted to an extension 52 of the trip lever 39, and the upper end of this pawl is normally held in engagement 115 with a notch in the adjacent end of the latch 48 by a spring 53. Thus, when the trip lever 39 is moved against the action of the spring 45 by the moving web of material, the pawl 51 will likewise be moved, and because of its engagement with the latch 48, will cause the latter to pass from the path of movement of the latch arm 48', so that the spring 28 will be free to operate until the 120 movement of the latch arm 48' is arrested by a stop 55. This engagement of the pawl 51 and the latch 48 is maintained until the tail 125 of the pawl contacts with a stop 54, at which time the pawl will be forced out of engage- 130

ment with the notch in the latch 48, and the 5 spring 50 will move the end of the latch 48 into engagement with the lower cam face of the shoe 49, so that upon the movement of the rod 25 in the opposite direction, and the consequent rotation of the shaft 24, the latch 48 will again be permitted to assume its original position and prevent the movement of the latch arm 48' until again released by the trip lever 39.

While the operation of the mechanism so far described is thought to be clear from the preceding description, a brief summary is here given. When the web of material is 15 fed beneath the stripper 42 and engages the trip lever 39, it moves the latter rearwardly, and upon such movement, the latch 48 is disengaged from the latch arm 48'. Immediately upon such disengagement, the engagement of the tail of the pawl 51 with the stop 54 disengages the pawl from the notch in the latch 48 and permits the spring 50 to force the latch into engagement with the shoe 49 of the latch arm 48'. When the 20 latch arm 48' is released, the spring 28 moves the rod 25 and through the connecting elements disengages the pawl 13 from the wear-block 14 on the cam lever 6, thus permitting the clutch spring to operate and engage the 25 clutch members. The engagement of these clutch members causes the rotation of the cam 8, and when this cam has completed a half revolution and the cam lever 29 moves to the high portion of the cam, the spring 30 28 is again put under compression and the pawl 13 reengaged through the arm 32 and the related elements. The latch arm 48' at this time moves to its initial position and the latch 48 again prevents its movement 35 until the trip lever is subsequently actuated. It may sometimes become desirable to move the clutch members into engagement by hand or to lock them out of engagement, and in order that this may be accomplished, 40 a controlling lever 56 is provided, which lever is pivoted at 57 to a support 58 having a pair of spaced notches 59 and 60. Pivoted to the lever 56 at 61 is a rod 62, which rod is, at its other end, slidably connected at 63 to the arm 12. When the lever 62 is in the 45 position illustrated in Fig. 3 and maintained in such position by the engagement of the spring-pressed pawl 64 in the notch 60, the operation of the clutch under the action of the sheet trip will be permitted. When, 50 however, the lever 56 is moved so that the pawl 64 engages in the notch 59, the arm 12, together with the arm 3, will be prevented from moving to permit the clutch members 55 to be interengaged, and, consequently, they will be locked out of co-operative relation. A rod 64 is connected to the lower end of the lever 56 and to a bell-crank lever 65, one 60 arm of which engages beneath a collar 66 on the link 15, so that when the lever 56 is

moved to its extreme right position, the link 15 will be moved upwardly, which will result in the disengagement of the latch 13 from the wear-block 14. Thus, the latch 70 may be tripped by hand and the clutch members permitted to interengage.

While a particular embodiment of the invention is illustrated and described, it is to be understood that various changes may be made in the construction of the various parts 75 without departing from the spirit of the invention and without exceeding the scope of the claims.

What is claimed is:—

1. In a machine of the class described, the 80 combination with clutch-controlling mechanism of an oscillatory shaft having a latch arm rigid therewith, means connecting said shaft with the clutch-controlling mechanism, a latch arranged to engage said latch arm 85 to prevent the movement of the shaft, and a trip lever for operating the latch to disengage the same from the latch arm.

2. In a machine of the class described, the 90 combination with clutch-controlling mechanism of an oscillatory shaft, a latch arm rigid therewith, means connecting said shaft with the clutch-controlling mechanism, a latch adapted to extend into the path of movement of the latch arm, means for maintaining the latch in such position, and means 95 for shifting it from such position.

3. In a machine of the class described, the 100 combination with an oscillatory shaft, of clutch-shifting mechanism connected to and controlled thereby, means for preventing oscillation of the shaft, and means for rendering the last-mentioned means inoperative.

4. In a web shearing machine, the combination with clutch-controlling mechanism 105 including a reciprocating member, an oscillatory crank arm to which said member is pivoted, a latch for preventing the movement of the crank arm, and a trip lever, having a pawl connection with the latch, for 110 controlling the operation of the latter.

5. In a machine of the class described, the 115 combination with a clutch rod, of an oscillatory arm positively connected therewith, a cam lever, a cam for controlling the latter, a latch connection between the cam lever and oscillatory arm, means controlled by the work for destroying the latch connection, and means for reestablishing said latch connection.

6. In a machine of the class described, the combination with an oscillatory shaft having a latch arm rigid therewith, of a latch adapted to engage the same to prevent its movement, a trip lever having suitable connection with the latch, for moving the latter, and means to destroy such connection upon a predetermined movement of the lever.

7. In a machine of the class described, the 130

combination with an oscillatory shaft, of a latch therefor, and a trip lever mounted on a common pivot, a pawl carried by the trip lever and engaging the latch, and means for disengaging the pawl from the latch upon a predetermined movement of the lever.

8. In a machine of the class described, the combination with an oscillatory shaft for controlling the operation of a clutch, of a latch arm depending therefrom, a latch arranged to engage the arm, a trip lever for controlling the latch, and a pivotally movable stripper, the lower end of the trip lever being extended through the stripper.

9. In a machine of the class described, the combination with an oscillatory shaft having a depending latch arm with a shoe on the lower end thereof, of a latch arranged to extend into the path of movement of the latch arm, a trip lever for moving the latch from such position, means for moving the shaft to bring the shoe of the latch arm above the latch, means for rendering the trip lever inoperative to further move the latch, and means for moving the latch into engagement with the shoe, whereby, upon the reverse movement of the latch arm, the latch will be returned to its initial position.

10. In a machine of the class described, the combination with a clutch-controlled cam, of a shaft, an arm rigid with the shaft and having connection to the clutch, a pair of reversely acting cam levers loosely mounted on said shaft, a latch for securing one of said levers to the shaft, means for rendering the latch inoperative, and means operated by the other cam lever for subsequently rendering said latch operative.

11. In a machine of the class described, a clutch-controlling mechanism, an oscillatory shaft, a reciprocating rod connected to said shaft and to the clutch-controlling

mechanism, means for moving the rod in one direction and means associated with the oscillatory shaft for controlling the movement of the rod.

12. In a machine of the class described, a clutch-controlling mechanism, an oscillatory shaft, a reciprocating rod connected to the shaft and to the clutch-controlling mechanism, means for moving the rod in one direction and a work-controlled trip mechanism for controlling the movement of the shaft.

13. In a machine of the class described, a clutch-controlling mechanism, an oscillatory shaft, a latch arm rigid with the shaft and having a cam shoe thereon, an operating connection between the shaft and the clutch-controlling mechanism, a latch arranged to prevent the movement of the latch arm in one direction, means for rendering the latch inoperative, means for engaging the latch with the cam face of the shoe, and means for arresting the movement of the latch arm while the latch is in engagement with the shoe.

14. In a machine of the class described, a clutch-controlling mechanism, an oscillatory shaft, a reciprocating rod connected to the shaft and to the clutch-controlling mechanism, a latch arm rigid with the shaft, a latch engageable with the latch arm to prevent the movement of the latter in one direction, a trip lever for rendering the latch inoperative, and a lost-motion connection between the trip lever and the latch, whereby the lever may continue its movement independent of the latch.

Signed at Rochester, in the county of Monroe, and State of New York, this 6th day of April, A. D. 1917.
